UNITED STATES PATENT OFFICE

ADOLF HEINRICH JUNKERS, OF RHEYDT, GERMANY

APPARATUS FOR TREATING YARN

Application filed September 24, 1929, Serial No. 394,900, and in Germany September 29, 1928.

The invention concerns an apparatus for accomplishing yarn treatments, which usually are accomplished on yarn hanks, as especially the brushing operation serving for the production of strong polished yarn (in Germany called "Eisengarn"), and other treatments by mechanically acting tools.

The essential feature consists therein, that the yarn is treated by brushes or the like in running state, while passing as a single yarn or as a group of several parallel yarns with freely extended multiple windings around two or more drums, whereby said drums have axles being essentially parallel and crossing each other in different planes, and have diameters being greater where the yarn shall have a greater length and smaller where the yarn shall have a minor length. Thereby a completely new mode of operation is attained. While in treating a hank the single yarn windings have never a completely uniform tension and lie over each other in multiple layers without order, in the new process the yarns have in all windings a desired tension in spite of lengthening or shortening of the yarn during the treatment and are exposed to the brushes or other tools in complete order and separation from each other, so that a by far more uniform treatment is ensured. Further, while in treating hanks only one or two circulations of the hank is used and any irregularity acts upon all yarn windings at once, so as to later appear on each winding, according to the invention each portion of the yarn passes all treating points after each other, so that a completely uniform treatment is ensured. Finally, while a hank can only slowly circulate, in the invention the yarn can run with such a high velocity, that the work becomes of still higher uniformity, and under certain circumstances the movement of the yarn may act as treating movement, the brushes or other tools remaining at rest and being more easily subjected to inspection and cleaning. Moreover the hank treatment, in consequence of the relative shortness of the hank, needs much knotting points, whereas in the invention any desired length of yarn can be made without knots,

and spools without knots can be produced.

The invention further concerns several details of the apparatus as further described.

In the accompanying drawings,

Figs. 1, 2 and 3 are an end view, partly in section, a lateral view and an enlarged partial top view of a winding device comprising a yarn treating device and a store inserted in the yarn running out from it.

In the machine according to Figs. 1 to 3 a great number of strands of a single yarn is extended in series. Several such arrangements may be united in a single machine having sufficiently long drums, but with each yarn wound round both drums in multiple threads. The arrangement is the following.

A casing 11 is partly closed by a front wall 12 and contains an inner division wall 13 and behind the latter a heating body 14. A fan 15 is connected to the fore compartment for sucking the air warmed on the heater 14 to the fore chamber and then leading it off, whereas fresh air enters from below to the heater.

In the fore chamber, two drums 16, 17 are mounted, the axes of which cross each other in different planes. In the illustrated example the lower drum 16 has its axis parallel to the longitudinal direction of the entire apparatus, whereas the upper drum is mounted obliquely in the horizontal plane, so that a yarn wound in many windings round the drums is able to continuously run round them with properly distanced yarn windings. A belt drive 18, shown in dash and dotted lines serves for driving both drums in equal direction. With strong yarn only one drum needs to be driven as the yarn suffices for driving the other.

The kind of crossing of the drum axes and the shape of the drums 16, 17 depends upon the kind of yarn to be treated and upon the kind of treatment.

If, for example, the yarn increases in length during the treatment, as in "mercerizing" or spinning, the shortest distance between both drum axes, the crossing point, as shown in Fig. 1 lies on the yarn entrance, so that against the yarn exit the drum distance is augmented more and more, and the yarn is everywhere held under tension. If

inversely the yarn decreases in length, the crossing point is arranged near to the yarn exit end of the drums. If the lengthening or shortening processes are discontinuous or stronger than may be made up by the different axis distances of the drums, then the drums are not made cylindrical but with diameters increasing from one cross section to another, so as to have conoidal or spheroidal or other shapes. The drums have increasing diameters on each spot where the yarn increases in length, and decreasing diameters on each spot where the yarn decreases in length, so that everywhere the yarn is under a desired tension and eventually stretched as desired.

A yarn tensioning device for guiding the yarn from a spool 19 to the machine is constructed as follows. Two small crossed feeding drums 20, 21 of essentially the same arrangement as the main drums 16, 17 receive the yarn, coming from the spool 19, in multiple yarn windings and deliver it over a roller 22 to the main drums 16, 17. For setting the yarn under tension, at least one of the drums 20, 21 is provided with a brake band 23 loaded by interchangeable weights 24 (or by a spring).

The yarn coming loosely from the spool 19 is hereby more and more set under tension as it surrounds more and more times the drums 20, 21, and runs with the desired tension, to the main drums 16, 17 without any damage, arising in other devices by friction, even if knots or other defective spots pass through the device.

A further yarn storing device is inserted into the yarn running out from the treating drums 16, 17, said device also consisting of a pair of small drums 25, 26 with axes crossing each other. These drums are also driven from the machine drive and surrounded by the yarn in multiple windings. These drums 25, 26 are held in bearings only on one end so as to allow the yarn to be drawn off over the other free head ends with a velocity independent upon the winding up velocity. The drive of said drums 25, 26 is a regulable one, the drums (or at least one of them) being driven by a conical pulley 27 which is axially displaceable against the main driving belt 18 of the entire machine. For guiding the yarn an oval circular guide cup 28 is arranged before the free ends of the drums 25, 26, over the edge of which cup the yarn runs in being drawn off. On said cup a guiding arm 29 is mounted which guides the yarn by a guide eye. Said arm 29 is mounted on a shaft 30 by aid of a frictional clutch (similar to a watch hand clutch), and the shaft 30 is driven by a belt drive 31 from any speed changing gear, such as stepped or conical pulleys, and said gear is driven from one of the drums 25, 26 and in the same direction as these.

The action is the following. If the spooling device draws off the yarn with a higher velocity than it is delivered from the treating device, more and more windings are drawn off over the head end of the device, the guide arm 29 being slowly rotated by the yarn against the driving force of its shaft 30 by overcoming the friction of its clutch. This most favorable case can usually be obtained by regulating the velocity of rotation of the winding up device in such way, that during the winding off and treating the yarn from a spool, the storing cores, which are fully wound up with yarn in the beginning, loose only a part of the yarn windings by drawing off over the head ends. If the spooling device operates with a smaller velocity than the treating device, the drive 30, 31 acts through the frictional clutch on the guide arm 29, so that the latter follows the yarn on the cores and augments the number of windings on them. This gives also the possibility of filling the cores with yarn windings in the beginning of operation.

In this way independently upon the entrance of yarn to the storing device, the yarn can be delivered to any winding device with any desired velocity and with a uniform tension regulated by the frictional clutch.

For automatically obviating an accumulation of too much windings on the delivering drums 25, 26 the following device is provided. Between said drums an oblique lever 32 with a balancing weight 33 is so arranged that it lies in the region of the last yarn windings on said drums. Thereby a sliding off of said windings over the heads of said drums is obviated, and an electric contact 34 is closed by said lever. A magnet coil 35 is thereby fed with electric current and attracts its core 36, which against the tension of a spring 38 displaces a belt fork 37 so as to displace the driving belt 18 of the spooling device on the conical pulley of the latter. This spooling device is thereby accelerated and detracts more yarn so as to diminish the number of windings on the drums 25, 26. Thereupon the contact 34 is again opened, and the normal running is restored. The oblique position of the lever 32 allows several sheets of yarn to press on said lever in unison, so that also very thin yarn can operate said lever without breaking. For strong yarn a simple upright lever is sufficient.

For treating the yarn, rotary brushes 42 are applied to the front and rear side of the front portion of the yarn extended between the main drums 16, 17. As said drums 16, 17 allow the yarn to run with very great velocities, sufficient as brushing velocities, the said brushes 42 need only to rotate with very small velocities in one or the other direction, so as to apply successively their different portions to the yarn and offer the other portions to inspection and, if necessary, to cleaning.

A drive with a circumferential motion coincident with the yarn running direction obviates the accumulation of dirt on the yarn, where it enters to the brush. In cases in which 5 this does not suffice, the brush may be driven with a circumferential velocity equal to the yarn running speed augmented by the necessary brushing speed.

Above the brushes 42, on a swinging shaft 10 43 a comb 44 is so mounted and driven by an elastic drive, that it swings up and down between the yarns and if desired swings fully out between them on the top end of the swinging motion, for separating yarns adhering to 15 each other. A drum 44' connected to said comb serves for being applied to the yarn when the machine is at rest, for holding the yarn under tension when the brushes or other tools are interchanged.

20 In some cases said comb 44 may also be stationary with the teeth under an acute angle with respect to the yarn, which then climbs over them, if, due to the yarns sticking together, the tension becomes too great.

25 For preparing the yarn to the treatment, in the inlet between the tensioning drums 20, 21 and the roller 22 three brushes 45, 46, 47 are applied to the yarn, the first brush 45 being moistened by water or steam, the second 30 brush 46 being filled with paraffin or a similar smoothening material, and the third brush 47 serving for distributing the water and paraffin and removing their abundance.

For cleaning the main drums 16, 17, which 35 are constructed as skeleton drums the following device is arranged. Each drum 16, 17 has on its ends smooth friction rims 48, and shafts 49 supporting cleaning drums 50 and friction rims 51 are mounted in elastically applied bearings in such way as to be driven from the drums 16, 17 by the friction rims 48, 51. Said cleaning drums 50 thereby grind on the skeleton drums so as to clean them from dye and other impurities deposited thereupon. They extend only over a portion of the 45 length of the main drums 16, 17 near the yarn entrance, as only in this portion impurities are encountered.

The operation of the entire machine is the 50 following. The dyed yarn runs from the spool 19, which eventually is enclosed in a usual steam chamber through the tensioning device 20, 21 to the brushes 45, 46, 47, of which the first brush 45 can be omitted especially in the case of using the said steam chamber, and after this preparation the yarn is polished by the rotary brushes and at once dried by the warm air current, each portion passing very often in succession the brushes 55 and the air current, so that completely polished yarn is produced. The spooling device forms said yarn immediately to spools ready for use.

The machine is also useful for different 60 other treatments of yarn, for example for

waxing, for quenching or stewing, or for brushing operations in naphtholic colouring processes. In much of these processes no moist and dyed spools are used, and therefore the drying device is not to be put in action. 70 For such processes the velocities of brushing or the like have to be altered as far as necessary, or the brushes are to be replaced by other tools. In all such processes the crossed drums are able to surely hold each yarn under 75 tension due to the adapted choice of the situation of their crossing point and due to the adaption of their diameter variations.

I claim:

1. An apparatus for treating yarn and especially polishing it, comprising in combination essentially parallel rotatable drums, the axles of which cross each other in different planes, so as to receive a yarn wound around said drums with freely extended multiple 80 windings arranged in the manner of a single thread screw, the diameter of said drums being greater where the yarn is of greater length and smaller where the yarn is of minor length. 85

2. An apparatus for treating yarn and especially polishing it, as claimed in claim 1, wherein a comb is inserted between the yarn sheets and driven so as to be swung to and fro between them in their lengthwise direction and fully out of touching them on the one end of the swinging motion. 95

3. An apparatus for treating yarn and especially polishing it, as claimed in claim 1, wherein a comb is inserted between the yarn sheets, the teeth of said comb being arranged under an acute angle with respect to the yarn in such direction, that the yarn under too great tension is able to climb over said teeth. 100

4. An apparatus for treating yarn and especially polishing it, as claimed in claim 1, wherein a separating wall is inserted between the drums and behind the treating tools, a compartment is provided behind said wall, and a warm air current generator is connected to said compartment so as to act on the yarn being extended behind said wall. 110

5. An apparatus for treating yarn and especially polishing it, as claimed in claim 1, wherein for tensioning the yarn running to 115 the drums a pair of small drums with axes crossing each other in different planes is inserted before said main drums, and at least one of said small drums is provided with a braking device. 120

6. An apparatus for treating yarn and especially polishing it, as claimed in claim 1, wherein to tension the yarn running from the drums a pair of small delivering drums with axes crossing each other in different planes 125 is inserted after said main drums, said delivering drums having one end free for axially drawing off the yarn, and at least one of said delivering drums being provided with a regulable drive. 130

7. An apparatus for treating yarn and especially polishing it, as claimed in claim 1, wherein for tensioning the yarn running from the drums a pair of small delivering drums with axes crossing each other in different planes is inserted after said main drums, said delivering drums having one end free for axially drawing off the yarn and covered by a cup guiding the yarn round its edge, and at least one of said delivering drums being provided with a regulable drive.

8. An apparatus for treating yarn and especially polishing it, as claimed in claim 1, wherein for tensioning the yarn running from the drums a pair of small delivering drums with axes crossing each other in different planes is inserted after said main drums, said delivering drums having one end free for axially drawing off the yarn, a guiding member is rotatably supported oppositely to said free end and adapted to guide said axially drawn yarn, braking means are provided on said guiding member, and a regulable drive is provided at least on one of said delivering drums.

9. An apparatus for treating yarn and especially polishing it, as claimed in claim 1, wherein for tensioning the yarn running from the drums a pair of small delivering drums with axes crossing each other in different planes is inserted after said main drums, said delivering drums having one end free for axially drawing off the yarn, a guiding member is rotatably supported on a driving shaft by aid of a friction clutch, oppositely to said free end and adapted to guide said axially drawn yarn, and a regulable drive is provided at least on one of said delivering drums.

10. An apparatus for treating yarn and especially polishing it, as claimed in claim 1, wherein for tensioning the yarn running from the drums a pair of small delivering drums with axes crossing each other in different planes is inserted after said main drums, said delivering drums having one end free for axially drawing off the yarn, and at least one of said delivering drums being provided with a regulable drive and an abutment is arranged near the free end of said delivering drums, so as to prevent the yarn from descending over said free end.

11. An apparatus for treating yarn and especially polishing it, as claimed in claim 1, wherein for tensioning the yarn running from the drums a pair of small delivering drums with axes crossing each other in different planes is inserted after said main drums, said delivering drums having one end free for axially drawing off the yarn, and at least one of said delivering drums being provided with a regulable drive, a contact lever is arranged near the free end of said delivering drums, so as to be depressed by a yarn travelling too far, and an electromagnetic de-

vice for regulating the velocity of drawing off the yarn is operated by said contact lever.

12. An apparatus for treating yarn and especially polishing it, comprising in combination two essentially parallel rotatable drums, means for rotating at least one of said drums, means for axially displacing a yarn wound round said drums in a plurality of windings, treating tools, such as brushes, applied to the yarn extended between said drums, and means for drawing off the yarn from said drums with regulable tension and speed independent of the speed of delivering the yarn to the bobbins.

13. An apparatus for treating yarn and especially polishing it, as claimed in claim 12, wherein a device for tensioning the yarn running to said drums is inserted before said drums.

14. Apparatus for treating and polishing yarn, comprising two essentially parallel rotatable drums, the axles of which cross each other in different planes, so as to receive a yarn wound around both said drums with freely extended multiple windings arranged in the manner of a single thread screw, the cross point of the axes of said two drums being arranged on that point of the length of the drums on which the yarn is of the shortest length, means for rotating one of said drums, and treating tools, such as brushes, applied to the freely running yarn extended between said drums.

In witness whereof I affix my signature.
